REGINALD G. SMITH AND EARL N. PERCY, OF OAKLAND, CALIFORNIA.

ORCHARD-HEATER.

1,091,170.

Specification of Letters Patent. Patented Mar. 24, 1914.

Application filed July 30, 1913. Serial No. 781,974.

To all whom it may concern:

Be it known that we, REGINALD G. SMITH, a subject of the King of England, and EARL N. PERCY, a citizen of the United States, both residing at Oakland, in the county of Alameda and State of California, have invented new and useful Improvements in Orchard-Heaters, of which the following is a specification.

10 This invention relates to orchard heaters and is particularly designed for the use of heavy mineral oil as fuel.

15 The invention consists of the parts and the construction and combination of parts as hereinafter more fully described and claimed, having reference to the accompanying drawings, in which—

20 Figure 1 is a vertical section on line X—X, Fig. 2. Fig. 2 is a horizontal section on line Y—Y, Fig. 1.

A is a liquid fuel containing receptacle of suitable size and shape having a tight fitting cover 2, provided with a gas outlet 3. Suitably supported on the cover and extending upwardly therefrom and surrounding the gas outlet 3 is a short inner stack 4 which is closed at the top by a cowl plate 5 for the purpose of directing the gases generated within the receptacle radially outward 25 through a series of small perforations 6 which are made around the top of the inner stack.

7 is an outer stack spaced from the inner stack and circumferentially supported on the 35 cover extending considerably above the closed or choked end of the inner stack having a series of perforations 8 around its base. The regulation of air through the holes 8 is accomplished by a perforated sleeve damper 9.

40 10 is a cover vent or orifice in the cover, primarily designed for ignition purposes and also serving as an air duct for admitting air into the receptacle.

45 11 is a perforated draft deflector and regulator consisting of a vertically disposed plate attached to or carried by the cover and disposed adjacent to one side of the receptacle.

50 12 is a covered orifice through which air is admitted to the flue 13 formed between the regulator 11 and the adjacent wall of the receptacle. While the plate 11 may be supported in any suitable fashion it is preferably provided with a flange 14 which sup-

ports the plate on the top of the cover when 55 the plate is dropped down through a slot 15 in the cover.

In practice the heater is filled with fuel oil to a point about 2" from the top and just below the top row of perforations in the 60 plate 11 and is ignited through the orifice 10 by means of a little gasoline and a torch. Air may be admitted for combustion purposes either through orifice 12 or vent 10 or both. If admitted through orifice 12 while 65 the heater is more than half full, too much gas will be formed, but after the oil in the heater has receded to less than one-half original depth, it becomes necessary to admit air through the orifice 12 behind the 70 baffle 11 in order that the air may have a downward direction and pass along the surface of the oil, thus permitting the heater to be burned out clean. The best operation of the heater is secured by so regulating both 75 orifices 10 and 12 that the combustion is as smokeless as possible. The combustion within the heater is for gas making purposes only. These products pass up the inner chimney 4 against the closed end 5 of the 80 chimney and out of the holes 6 in the top in a horizontal direction where they are met by the current of air rising in the passage 16 and are ignited at the point of junction of the air and gases through holes 6 where secondary combustion takes place. This secondary combustion may be started either by ignition from the interior of the heater or by exterior artificial ignition. The draft upon which the interior operation of the heater is 90 dependent is induced by the chimney 7. The incoming air at the base of the outer chimney may be regulated and controlled by the damper 9.

It has been found advisable in practice 95 that the orifices for the admission of the air to the base of the outer chimney extend slightly above the top of the inner stack but not enough so as to decrease the draft induced by the outer chimney 7. The function of the inner chimney 4 is to create sufficient draft to maintain the gas making process. This being added to by the additional draft of the outer chimney 7 experience has demonstrated that smokeless combustion cannot be obtained with the outer chimney alone.

The present construction in its various

details prevents the heater from being unduly sensitive to outside influences, such as wind, etc., and being easily extinguished.

The advantages of the heater are that it is 5 smokeless and economical with minimum deposits of soot within the heater. The heater burns out clean excepting for a very small amount of dry residue. Any kind of oil can be used. All parts of the heater can be 10 stacked for transportation. The draft and air connections are adjustable. The gas making can be entirely regulated by the shutters of orifices 10 and 12 and the combustion of this gas regulated by the air inlet 15 shutter 9, thus making the heater universally adjustable. By these adjustments the heater may be regulated for any kind of oil or any conditions under which it may be operating, and for any size of fire.

20 The fundamental feature of our construction, aside from burning the pot out cleanly, is the small fire in the vicinity of the plate which rises and flows to the stack without transmitting very much heat to the large 25 exposed oil surface. As the oil recedes and becomes heavier through excessive fractioning, it reaches a point where it is advisable and necessary to increase the surface exposed to the flame, and to intensify the heat of the 30 combustion at the bottom of the pan, and to increase the amount of air admitted at that point. This is automatically accomplished by the uncovering of the lower end of the plate by the receding oil, permitting 35 the air to pass underneath, burning the pan out clean. When this occurs in our construction an increased area is affected by the increased combustion at the bottom of the pot.

40 Having thus described our invention what we claim and desire to secure by Letters Patent is—

1. In an orchard heater, the combination 45 of a liquid fuel containing receptacle having a close fitting slotted cover, said cover hav-

ing a gas outlet and a combusting stack in conjunction with the outlet, and draft directing means comprising a vertically disposed plate having a horizontal flange along its top edge by which said plate is suspended 50 through the slot in the cover to one side of the stack and projecting into the receptacle, and to a point adjacent to the bottom thereof, said plate forming with the adjacent wall of the receptacle a down draft flue, 55 said cover having a regulated air inlet into said flue whereby air is admitted to the receptacle in a down draft and delivered approximating to the surface of the oil as the oil recedes.

2. In an orchard heater, the combination of a liquid fuel containing receptacle having a close fitting cover, said cover having a gas outlet remote from one side of the receptacle, a combustion stack in conjunction with said outlet and a vertically disposed plate adjacent to the side of the receptacle remote from the gas outlet, said plate forming a partition across the receptacle and dividing the space above the fuel into two chambers, 65 means for admitting air from the outside to each chamber, said plate being perforated at different levels and said plate terminating short of the bottom of the receptacle, so that as the oil recedes and becomes heavier and 70 it becomes necessary to intensify the heat of the combustion at the bottom of the receptacle and on each side of said plate, the air may be admitted freely below the lower edge of the plate, and means for controlling 75 the amount of air admitted to the receptacle at either side of said plate.

In testimony whereof we have hereunto set our hands in the presence of two subscribing witnesses,

REGINALD G. SMITH.
EARL N. PERCY.
